UNITED STATES PATENT OFFICE.

JOHN S. BAKER, OF LOS ANGELES, CALIFORNIA, ASSIGNOR, BY MESNE ASSIGNMENTS, TO ANDERSON-BARNGROVER MFG. CO., OF SAN JOSE, CALIFORNIA, A CORPORATION OF CALIFORNIA.

COOKING APPARATUS.

1,315,074.

Specification of Letters Patent.

Patented Sept. 2, 1919.

Application filed August 21, 1916. Serial No. 116,092.

To all whom it may concern:

Be it known that I, JOHN S. BAKER, a citizen of the United States, residing at Los Angeles, in the county of Los Angeles and State of California, have invented certain new and useful Improvements in Cooking Apparatus; and I hereby declare that the following is a full, clear, and exact description thereof, reference being had to the accompanying drawings, which form part of this specification.

This invention is a novel improvement in cooking machines of the type shown in my Patent #1,182,832 of May 9, 1916; and the object of the present invention is to enable cans to be discharged from any desired run of the canway and at the same time to always maintain a substantially uniform control or closure of the discharge; to do away with a multiplicity of adjustable devices for varying the discharge of cans; to simplify and cheapen the construction of the machine, and to provide a construction which can if desired be readily adapted for use in cooking goods requiring high temperatures.

The invention also provides means for maintaining any desired uniform depth of water in the cooker; also novel means to insure the dropping of the cans from the carry-off devices; and to provide novel means for shifting the discharge openings of the canway. The invention also provides other novel detail improvements hereinafter mentioned; but the principal feature of the present invention is a novel slidable means for varying the point of discharge of the goods; this and the other novel features of the invention will be clearly understood from the following description in connection with the accompanying drawings which illustrate one practical embodiment of the invention and will enable those skilled in the art to adopt and use the same.

In said drawings:

Figure 1 is a sectional side elevation of a cooking machine of the general type shown in my aforesaid patent.

Fig. 2 is a front end view of such machine.

Fig. 3 is an enlarged sectional view of one end of said machine.

Fig. 4 is an enlarged detail front view showing the adjustable discharge slide.

Fig. 5 is an enlarged detail view of the carry-off devices.

Fig. 6 is a detail section on line 6—6 Fig. 4.

Referring to said drawings, 1 designates a tank which may be of any suitable construction, and is shown as provided with an internal spiral canway 1^a, constructed substantially as described in my aforesaid patent. The cans may be fed onto this canway 1^a through a feed chute or chutes 2^a, and the cans entering the cooker through the right hand chute 2^a will pass into the first run of the spiral canway.

The cans may be fed and discharged at the same end of the cooker; or at both ends if desired. The end wall of the cooker may be formed of a metal plate 4 to which the feed chute 2^a is attached. This metal plate 4 has an enlarged opening 4^a in it extending substantially across all the runs of the canway or the entire width of the series of canways.

On the lower edge of this opening is a groove 4^b in which is supported the lower edge of a transversely movable sliding plate 5, the upper edge of which is confined in the upper edge of the opening and guided in a groove formed between the upper outer edge of the plate and a bracket or casting 6 rigidly attached to the plate 4 above the upper edge of the opening. The slide 5 can be slid back and forth transversely of the cooker and beneath the feed opening, being retained and guided in position as described.

The slide 5 may be made longer than the width of the tank, according to the number of runs in the canways, or the number of different points at which it may be desired to discharge cans. The slide is provided with an opening 5^a through which the cans pass out into a receiving trough 7 herein-after referred to.

The casting 6 not only forms a guide and retainer for the upper edge of the slide 5, but is also provided on its front edge with a rack 6^b beside the upper edge of the slide 5 which rack is engaged by a pinion 5^c attached to a hand wheel 5^d mounted on a stud 5^e attached to slide 5. As the rack 6^b is

fixed, if the hand wheel 5¹ is turned, it will by reason of the engagement of pinion 5¹ with the rack 6^b move the slide 5 right or left, according to the rotation of pinion 5¹, 5 as the hand wheel being rotatably mounted on the slide, the slide must move with it.

This pinion 5¹ is preferably of such size that one full revolution thereof will move the slide 5 the width of one runway of the 10 spiral canway, and therefore the discharge port 5^a which of course moves with the slide, can be readily shifted opposite any run of the canway.

I preferably place a hood 5^b over this discharge port 5^a, and in the top of the hood is a vent opening 5^c which may be connected with a flexible pipe or hose 5^d in any suitable manner; see Figs. 2 and 6. The reasons for this hood is that it will carry off the steam 20 through the roof of the cannery, and same will not come out in the factory. The flexible pipe or hose 5^d can be extended up through the roof of the building; and as the steam passes out of the cooker through 25 the discharge port 5^a the steam will be sucked up into the pipe 5^d. Where a number of different lengths of cooks are run daily, it may be desirable to omit this hood, so that the operator can conveniently see the 30 position of cans in the canway before setting his discharge, and can see just what cans to take out of the machine, and what cans to let go by.

The cans discharged through the outlet 5^a 35 may be directed into a trough 7, wherein they may be moved by an endless carrier 7^a operated by sprocket wheels 7^b and chains 7^c running over sprocket 7^d suitably actuated from the drive shaft. This carrier removes 40 the cans in the trough to one side of the tank. At the outer end of the trough 7 is a knock-off rod 7^e arranged diagonally of the conveyer, and a knock-off shoe 7^f, see Fig. 5. The knock-off rod is pivoted at 7^g to one side 45 of the trough and its other end is adjustably fastened by a bolt and nut 7^h. As the cans are moved in the trough 7^a by the carrier they first engage the knock-off rod 7^e and then contact shoe 7^f by which they are deflected out of the trough 7 into a chute 7^x, 50 which directs the cans to a cooler or other suitable point of discharge.

As the can is brought forward on conveyer 7^a the knock-off rod 7^e tends to roll the can laterally off and on the carrier and at the proper point the can contacts knock-off shoe 7^f which starts the cans toward the chute 7^x.

The knock-off shoe 7^f is provided with a 60 device or tappet 7^g which is adapted to be contacted by the front end of a can, near the rear side thereof, just as the can contacts with the knock-off shoe 7^f. And the contact of the can with the device 7^g causes 65 the can to straighten out as indicated in dot-

ted lines in Fig. 5 parallel with the conveyer, and properly enter the chute 7^x.

The cans fed into the machine are moved around the canway by means of a series of pusher bars 1^e carried by endless chains 1^d as 70 described in my aforesaid patent; it sometimes happens that these bars become bent and it is important that they should not catch on any projections, and therefore I provide guards or deflectors 8 below the 75 inner end of the feed chute, see Figs. 1 and 8, so that in case any pusher bar gets bent in any way, these guards 8 will deflect such bent pusher bar inwardly so that it will not cause any damage to the machine. 80

In order to maintain a proper level of water in the tank, I preferably provide an overflow 9, which extends up from the bottom of the tank, and the water when it 85 rises to the level of the upper end of pipe 9 overflows down through same and out through an elbow at bottom. The main principle, of putting the overflow at bottom of tank as shown is that the full area of the 90 overflow pipe is always in use as soon as the water flows over same. This overflow pipe can be adjusted up or down by means of lock nuts at 9^a to adjust the water level in the cooker. 95

It will be observed that in the machine shown in the drawings the cans can be fed for example at the right hand end of the machine and be caused to traverse any desired number of coils or spirals of the canway until they reach the discharge port 5^a, 100 which can be set by adjusting the slide 5 opposite any desired run of the canway. If set opposite the run of the canway farthest removed from the feed end thereof, the cans 105 would have to traverse the entire canway. If it be set at an intermediate run of the canway the cans can be caused to traverse more or less of the runs of the canway. In this way any desired length of cook can be given 110 to the goods without altering the speed of travel of the cans, simply by adjusting the slide 5 longitudinally or transversely of the canway.

The chamber practically remains closed at 115 all times except for the discharge opening, but the operator can readily determine when the discharge opening is opposite the proper run of the canway. If desired suitable indicating marks, not shown, can be placed on 120 the exterior of the tank to enable the operator to properly adjust the slide; but if the hood 5 is removed such indication would not be necessary. If a delivery slide be arranged at each end of the machine the number of 125 possible discharge points would be correspondingly increased. If a plurality of feeds should be arranged at the same or opposite ends of the machine, it will be possible to simultaneously feed and deliver a 130

plurality of series of cans through the machine at the same time and give each series any desired length of cook, or the same or different lengths of cook as desired.

5. An essentially novel feature of this invention is having the discharge controlled by a slide having a single opening, such slide being adjustable so as to bring this opening into register with any desired run of the canway. Another feature of the invention is novel means for taking off the steam in case high temperatures are desired in the cooker. By means of the pipe 9 the water in the cooker can be maintained at the proper level 10 at all times. The device for discharging cans from the trough into the chute 7^a is also very useful and is particularly efficient. The device 7^a operates to straighten out the cans and cause them to enter the chute 7^a properly just at the moment they roll off of the carrier 7^a.

As shown in Fig. 1 instead of having the discharging device duplicated at each end of the machine the cans may be guided around the rear bends of the canway by an adjustable curved plate 10 hinged or adjustably attached at its bottom in any suitable way to the bottom plate of the canway, as indicated at 10^a. This plate is adjustable so that the 25 space between its inner face and the curved portions of the bars can be varied to suit cans of different size and properly direct them around the bends, by swinging or adjusting the plate inward or outward. As 30 shown the upper end of the plate can be adjusted by means of bars 11 pivotally connected to the plate at their inner ends, and projecting outwardly through openings in the wall of the tank and provided with notches 35 11^b which can be engaged with the end wall of the tank to hold the plate in the desired 40 adjusted position. The plate may also be further supported and adjusted if desired by any adjusting screw or screws 12 extending 45 through the end wall of the tank and engaging the central portion of the plate as shown.

While I have referred in this description to the use of cans I have done so simply as 50 illustrative and not as limiting the invention, for the apparatus can be used for treating packaged goods of any desired kind, although the invention is particularly designed for use in cooking canned goods or 55 goods in cylindric packages which can be rolled along the ways.

I claim:

1. In a cooking apparatus the combination of a chamber, a spiral canway therein, 60 a member having an outlet, and means for adjusting the member to cause the outlet to conform with any run of the canway from which it is desired to discharge cans.

2. In a can cooking apparatus the combination of a casing providing a cooking cham-

ber, a spiral canway therein, a member having an opening, and means for adjusting the member so as to bring the opening into register with any run of the canway from which it is desired to discharge cans.

70

3. In a can cooking apparatus the combination of a casing providing a cooking chamber, a spiral canway therein, an adjustable slide adjacent the canway having an opening which may be brought into register with any desired run of the canway to permit escape of cans from the canway.

75

4. In combination, a cooking chamber having a feed opening, and a plurality of discharge points, a member for covering said discharge points and provided with an outlet opening, and means for positioning said member to bring its outlet opening in register with any of said discharge points.

80

5. In combination a cooking chamber, a spiral canway therein, means for moving cans along said canway, an opening adjacent one end of the canway and extending past a plurality of runs thereof, a slide closing said opening and having an outlet opening, and means for adjusting said slide to bring said outlet opening into register with any desired run of the canway.

85

6. In a cooker the combination of a chamber, a feed chute extending into the chamber, a series of pusher bars for moving cans in the chamber, and guards adjacent the inlet end of the feed chute adapted to prevent the pusher bars catching on the feed chute.

90

7. In a cooker the combination of a tank, a spiral canway therein, a feed chute extending into the tank adapted to deliver cans onto the canway, a series of pusher bars for moving cans around the canway, and guards adjacent the inlet end of the feeding chute to prevent the pusher bars catching on the feed chute.

100

8. In a cooking apparatus, the combination of a chamber, a spiral canway therein, a member having a port and means for adjusting the member to cause the port to conform with any run of the canway into which it is desired to feed cans.

110

9. In a cooking apparatus the combination of a casing provided with a discharge opening extending transversely of the runs of the can-way, a spiral can-way located in said casing, and a closure for said discharge opening having a can discharge outlet registering with the discharge opening in the casing and adjustably mounted on the casing, said closure being adapted to effect the discharge of the cans from any convolution of the spiral can-way and prevent the discharge of cans from the other convolutions thereof.

115

10. In a cooking apparatus the combination of a casing providing a cooking chamber and having an opening transversely thereof, a spiral can-way located in said

120

125

chamber, a slide adjustably mounted on the casing at said transverse opening and having a can discharge outlet adapted to selectively register with the spiral convolutions to discharge the cans, and a rack and pinion for actuating said slide.

11. In a cooking apparatus the combination of a casing providing a cooking chamber and having an opening transversely thereof, a spiral can-way located in said chamber, a slide mounted on said casing at said transverse opening and having a discharge outlet adapted to selectively register with the spiral convolutions to discharge the cans, a manually-operable device for actuating said slide, and means for holding said actuating device in set position.

12. In a cooking apparatus the combination of a casing providing a cooking chamber and constructed with a horizontally disposed curved portion, said curved portion having an opening formed therein, a spiral can-way located in said chamber and arranged in proximity to said opening, a slide mounted on the curved portion of the casing at said opening and having a discharge opening adapted to selectively register with the respective spiral convolutions to allow the cans to discharge therefrom by gravity; and means for actuating said slide and securing the same in adjusted position.

In testimony that I claim the foregoing as my own, I affix my signature.

JOHN S. BAKER.
